UNITED STATES PATENT OFFICE

WILLIAM F. EAMES, OF WILKINSBURG, PENNSYLVANIA, ASSIGNOR TO WESTINGHOUSE ELECTRIC & MANUFACTURING COMPANY, A CORPORATION OF PENNSYLVANIA

SELECTIVE SIGNAL SYSTEM

Application filed October 11, 1929. Serial No. 398,943.

My invention relates to systems of signal and control for elevators, hoists and similar machinery, and more particularly to signal systems for groups of elevators operated as 5 a bank.

In multi-storied buildings, it is common practice to employ a single up-and-down passenger-operated push-button station at each of the floors, so arranged that the call- 10 receiving means of all the elevators serving the building shall be responsive thereto. In such systems, it is, of course, undesirable that more than one of the cars shall make a stop at a given floor in response to a signal, 15 since, under such condition, the cars tend to "bunch" and proceed down or up the hatch-way together. Further, for all but the first of the cars to respond to the signal, the time spent in stopping is lost, since the needs of 20 the intending passenger are met by the first car to stop.

In an ideal system employing a bank of elevators, each floor would be served by an elevator at regularly spaced time intervals. 25 In other words, a definite spacing would be maintained between all of the elevators in the bank. Such is not possible, however, on account of the different traffic demands of the different floors. It is possible, however, to 30 so arrange the signal system that a car, having received a signal for service at a given floor, is the only car in the bank which is effective to receive calls for service at that floor, for a particular direction, until such 35 a time as that car has moved away from the floor, and to further so arrange the signal means for the cars that such first car is the only car the signal means of which is effective to receive calls for service at one or more 40 floors in advance of the floor at which the first call was registered. With such a system, only the first car to approach a floor receives the calls for that floor, and by "block- 45 ing" off the succeeding floors, an automatic spacing is maintained by the various cars. Such a system is disclosed in the copending application of F. E. Lewis, No. 388,310, filed August 26, 1928 and assigned to the West- 50 inghouse Electric and Manufacturing Com-

The majority of the signal systems now in use do not embody the features of "selectivity" and "blocking" just described. As a consequence, in installations so equipped, until such a time as a registered call has been 55 cancelled by an answering car, any other cars also in a position adjacent to the selected floor are also caused to stop in response to the one signal.

The time at which the call is cancelled varies 60 considerably in different systems. In some, it is cancelled immediately upon being received by an approaching car, and, in others, the cancellation does not take place until the car has come to a stop. In the former case, 65 additional calls may be set up by intending passengers approaching a floor at which a call has already been registered but which is as yet unanswered. In both cases, all cars within a predetermined distance of the floor, 70 and traveling in the proper direction, are caused to stop in response to a signal or signals that require the services of only one car.

To adapt existing signal systems to employ the "selective" and "blocking" means 75 described in the copending application to Lewis, above referred to, would, in most cases, involve considerable expense and lost time, if not a complete reorganization of such existing signal systems. 80

It is an object of my invention, therefore, to provide means whereby signal systems, which do not embody the feature of preventing more than one car from stopping in response to the same call, may be modified to 85 embody this feature without the necessity of completely changing them.

Another object of my invention is to provide means whereby signal systems, which do not embody the "blocking" feature hereinbefore described, may be modified to provide this feature without the necessity of completely changing them.

Another object of my invention is to provide means that may be added to existing 95 signal systems, without destroying the usefulness of any of their elements, to provide the described features of "selectivity" and "blocking" for such systems.

My invention will be described with ref- 100

erence to the accompanying drawings, in which:

Figures 1, 2, 3 and 4 jointly constitute a diagrammatic view of my signal system, as applied to a bank of two elevator cars.

Referring to the drawings, I have illustrated therein two elevator cars designated, respectively, by the reference characters C_A and C_B , each of which is equipped with a suitable controlling mechanism for governing the operation of the associated elevator comprising a car switch CSA , an up-direction switch $1A$, a down-direction switch $2A$ and accelerating switches $3A$ and $4A$ for car A , and a car switch CSB , an up-direction switch $1B$, a down-direction switch $2B$ and accelerating switches $3B$ and $4B$ for car B . Operation of the respective car switches will control the starting and acceleration and the automatic slow down and stopping means for the associated car.

I have illustrated the slow-down and stopping means as being of the inductor-landing type, similar to that described in the copending application of E. M. Bouton, Serial No. 731,291, filed August 14, 1924, and assigned to the Westinghouse Electric and Manufacturing Company, wherein a plurality of inductor relays, each comprising a coil and a movable armature, are mounted on the elevator car and are adapted to cooperate with inductor plates mounted in the hatchway adjacent to the floor levels to thereby control the deceleration and stopping of the car. I have illustrated a system wherein each car is provided with three running speeds, namely, a low landing speed, an intermediate speed and a higher speed. Accordingly, car A is supplied with a stopping inductor relay SRA , an up-direction intermediate-speed inductor relay $1LUA$, a down-direction intermediate-speed inductor $1LDA$, an up-direction high-speed inductor relay $2LUA$ and a down-direction high-speed inductor relay $2LDA$. Cooperating inductor plates (each indicated by a primed reference character corresponding to the relay it controls) are located in the hatchway at predetermined points in advance of the floors. Similarly, car B is provided with inductor relays SRB , $1LUB$, $1LDB$, $2LUB$, and $2LDB$ and inductor plates (bearing corresponding primed reference characters) positioned in the hatchway, as described for car A .

I have illustrated the motive means for each car as being of the variable-voltage type, wherein the field excitation of a generator is varied to cause a variable voltage to be supplied the elevator-hoisting motor, to thereby cause the hoisting motor to operate between predetermined speed limits.

For car A , I have provided a hoisting drum DA , over which passes a cable CaA to one end of which is secured the elevator car CA , and to the other end of which is secured a

suitable counter weight CwA . Rigidly connected to the hoisting drum DA is the shaft of the hoisting motor EMA , the field $EMFA$ of which is shown as being excited from a separate source, and the armature $EM'A$ of which is connected in loop circuit with the armature $G'A$ of the generator GA . The generator GA is provided with a series field winding $GSFA$ and a separately excited field winding GFA . The generator GA is directly coupled to a driving motor MA , illustrated as being of the shunt-wound type, with its armature $M'A$ and field windings MFA connected in parallel relation and energized from a separate source. A similar motive means is provided for car B , the elements of which are designated by the reference character "B", instead of "A", as described for car A .

I have illustrated the elevator cars A and B as serving five floors, indicated by the dotted lines bearing the legends 1st, 2nd, 3rd, 4th and 5th, respectively. Each of the floors intermediate the terminal floors is provided with suitable passenger-operated floor buttons for registering calls for service for the up and down directions, respectively. The buttons at the second floor comprise an up button $2FU$ and a down button $2FD$, and buttons $3FU$, $3FD$, and $4FU$ and $4FD$ perform corresponding functions at the third and fourth floors, respectively. Since the car always makes a complete trip from terminal to terminal, no floor buttons are provided for the terminal floors. Associated with each of the floor buttons is an actuating coil and a cancellation coil designated as $2FRD$ and $2FCU$ for the second floor down-direction, and as $2FRU$ and $2FCU$ for the second floor up-direction. Similar actuating coils $3FRU$, $3FRD$, $4FRU$ and $4FRD$, and cancellation coils $3FCU$, $3FCD$, $4FCU$ and $4FCD$ perform corresponding functions at the third and fourth floors. The floor buttons, when operated, therefore, remain in operative condition, although the floor button may be released, until such a time as the cancellation coil is actuated to cancel the registered call. The actuating and cancellation coils are associated together in a manner described in United States Patent No. 634,220 and issued to Messrs. Smalley and Reiners, whereby, upon energization, the actuating coil retracts an associated armature to permit the movable armature of the associated cancellation coil to make contact with a mercury-pot terminal to thereby complete the signal circuit. Upon actuation of the cancellation coil, its armature is withdrawn from the mercury-pot terminal and is again latched by the armature of the now deenergized actuating coil.

It will be understood that the floor buttons described are connected, through suitable parallel circuits, to all of the cars in the bank.

Also associated with the several floor buttons are resistors $2RU$, $2RD$, $3RU$, $3RD$,

4RU and 4RD, for the up and down directions at the second, third and fourth floors, respectively. The resistors are common to the call-registering circuits for the several 5 cars, and it will be apparent, therefore, that, upon completion of a circuit to the call-registering means for one of the cars through the resistor associated with the floor at which the signal originated, the voltage drop across 10 such resistor will be considerably less than would be the case if the call-registering circuits of two or more of the cars had been completed through that resistor simultaneously. Conversely, when a circuit is completed 15 through a resistor for the call-registering means of only one car, the voltage drop across such individual registering means will be considerably greater than would be the case if circuits were completed through a resistor 20 for two or more of the individual call-registering means simultaneously.

Since the coils of the relay means may be so designed as to require considerably more voltage to actuate the associated relay than 25 is required to maintain such relay in the actuated condition, it is apparent that it is possible to interpose in the car-receiving circuits of the individual elevator cars, relays so selected as to be actuatable by the voltage available 30 through a resistor when only one of such relays is supplied with voltage, but to be not actuatable by the voltage available through the resistor when two or more of such relays is supplied with such voltage simultaneously. A relay, once actuated, however, will remain so in spite of the reduced voltage available on completion of circuits to others of said relays. Therefore, by suitably 35 selecting the several resistors and the several 40 relays, only one of the relays will be actuated at any given time, and, hence, the call-receiving circuits for only one of the cars may be completed at any one time.

I have provided, therefore, two relays for 45 car A, designated by reference characters C2A and C1A, of identical design, and selectively operable according to the distance in advance of the floor of the car at the time the signal is established at the associated floor 50 button. The characteristics of the coils of relays C1A and C2A are such that, used in conjunction with the resistors I prefer to use, they will actuate their associated relays when the circuits for two of such relays are completed simultaneously. I have provided, therefore, that, upon actuation of any one of such relays, an additional resistor is interposed in shunt relation to such energized coil, to thereby increase the voltage drop across 55 the main resistor. Accordingly, when one of such relays is actuated, the combined effect of the additional associated resistor and of the main resistor is sufficient to render the voltage available to the coils of other relays, 60 the circuits for which are subsequently com-

pleted, below their actuating or "pick-up" value.

Similarly, I have provided relays C1B and C2B for car B and it will be understood that all cars in a bank would be so equipped. 70

In order that passengers on the car may signify their desire to leave the car at the intermediate floors, I have provided car buttons CA2, CA3 and CA4 for these floors, respectively, on car A. The buttons are maintained in the actuated condition when actuated by means of mechanical latches which are withdrawn at the end of each trip by action of a releasing coil CCA connected for energization through a floor selector, as hereinafter described. Car B is, of course, similarly equipped. 75

In order that intending passengers, having registered a call for service at one of the floors served by the elevator, may be advised of the approach of the car receiving such call, I have provided a plurality of floor lanterns for each car, to be mounted in the corridors adjacent to their associated cars. For car A, floor lanterns 1LA and 5LA are disposed at the terminal landings while floor lanterns 2LUA, 3LUA and 4LUA serve to advise of the approach of a car in the upward direction at the second, third and fourth floors, respectively, and lanterns 2LDA, 3LDA and 4LDA perform similar functions for downwardly moving cars for these floors, respectively. Corresponding lanterns are also provided for car B, with the reference character "B" replacing "A". 80

Cars A and B are provided, respectively, with suitable floor selectors FSA and FSB, which are operable correspondingly to the position of the cars with respect to the floors to complete certain of the control and signal circuits at predetermined points in the travel of the car. The floor selector for car A is illustrated as comprising a plurality of lines of conducting segments disposed upon a suitable base to be engaged by contact brushes on a movable arm MA, connected for upward and downward movement in accordance with the position of the car, by means of a suitable driving device illustrated as a screw 20. The various lines of segments on the floor selector FSA are divided into groups 110 21, 22, 23, 24, 25, 26, 27, 28, 29 and 30. Those groups on the left-hand side of the screw 20 are associated with circuits for the up direction of travel and those on the right-hand side are associated with circuits for the down direction of travel of the car A. 115

It will be understood that, when the car is in any given position with respect to a floor, the dash line marked "floor level" on the movable arm MA will be in a corresponding position with respect to the dash line on the floor selector FSA representing that floor. 120

The lines of segments in group 21 are design- 125

nated Y and X, line Y comprising a segment extending the entire length of the floor selector FSA and line X comprising four segments, each extending approximately the distance between adjacent floors. Lines X and Y may be connected by means of brushes 21b and 21c on the movable arm MA and are associated with the circuits for the various up-direction floor lanterns.

The lines of segments in group 22 are designated X, Y and Z, the segments in line X being coextensive with the segments in line X of group 21, and the segments in line Y and Z being coextensive with the segment in line Y of group 21. Lines X and Z of group 22 may be connected by means of brush 22a on the movable arm MA, to complete the several call-receiving circuits originating at the floor buttons through blocking relay C2A, while lines X and Y may be connected by means of brush 22b on movable arm MA, to complete these circuits through the blocking relay C1A.

The lines of segments in group 23 are designated X, Y and Z, the segments in line X being coextensive with those in line X of group 21, while the segments in lines Y and Z are coextensive with the segment in line Y of group 21. Lines X and Y, and X and Z may be connected by means of brushes 23b and 23a, respectively, on the movable arm MA, to complete the several call-receiving circuits originating at the car buttons CA2, CA3, and CA4.

The lines of segments in group 24 are designated X and Y, the segments in each being coextensive with the segments in lines X and Y of group 21, respectively, and may be connected by means of brush 24c on movable arm MA, being associated with the call-cancellation circuits for the various floors.

The lines of segments in group 25 are designated X and Y, the segment in line Y being coextensive with the segment in line Y of group 21. In line X of group 25 is one short segment disposed approximately midway between the 4th and 5th floor dash lines. The segments in lines X and Y may be connected by means of a brush 25c on the movable arm MA to complete a circuit for the coil USA of the reversing relay 31, next to be described.

As noted, the segments to the left of the screw 20 are associated with circuits employed in the up direction of travel, and those to the right are associated with circuits employed in the down direction of travel. The relay 31 is provided with two actuating coils, USA and DSA, energization of which causes its armature to be moved to the right or to the left, respectively. A spring 32 serves to maintain the armature in the position established by the momentary energization of either coil USA or coil DSA.

The armature of relay 31 is provided with

eight pairs of contact members a, b, c, d, and a', b', c', and d', the first four of which are associated with travel in the up direction and the last four of which are associated with travel in the down direction. Thus, it will be observed that, when the car is traveling upwardly, the contact members a, b, c and d will be closed, being maintained in that position by spring 32. However, when brush 25c connects segments 25 X and Y, as the car approaches the upper terminal, coil USA is momentarily energized to move the armature of relay 31 to the right, opening contact members a, b, c and d, and closing contact members a', b', c' and d', thereby conditioning the system for travel in the down direction. Similarly, as the car nears the lower terminal in a down trip, coil DSA will be energized to open contact members a', b', c' and d' and close contact members a, b, c and d. A similar relay 31' is provided for car CB.

The segments in lines 25 and 26 also control the energization of the resetting coil CCA for releasing the car buttons, as described.

On the movable arm MA I have drawn two additional dashed lines through the centers of the b brushes and the a brushes, respectively, and have made the notation that the a line of brushes is one and one-quarter floors, and the b line, one half of one floor, in advance of the c line of brushes.

I will be noted that I have provided three separate supply voltages, namely, L1—L2, L3—L4, and L5—L6. Since it is my object to demonstrate the applicability of my blocking relays and resistors to existing systems, I have taken a characteristic voltage arrangement, wherein L1—L2 is 230 volts direct current and feeds the main control and motor circuits, L3—L4 is 17 volts alternating current and feeds the signal actuating and cancellation-coil circuits, and L5—L6 is 110 volts alternating current and feeds the various signal lamps and hall lanterns.

My invention may best be understood with reference to an assumed operation. Assuming that it is desired to move the car upwardly, the operator may move the car switch CSA in a counter-clockwise direction to complete a circuit for up-direction switch 1A, which circuit extends from line conductor L1, through conductor 40, contact members 41, 42 and 43 of car switch CSA, conductor 44, the coil 58 of up-direction switch 1A, conductors 45 and 46, contact members 47 of stopping inductor relay SRA, and conductors 48 and 49 to line conductor L2.

Upon closing, up-direction switch 1A completes a circuit for the separately excited field winding GFA of the generator GA, which circuit extends from line con-

ductor L1, by way of conductor 50, contact members *b* of up-direction switch 1A, conductors 51 and 52, the field winding GFA, conductors 53 and 54, contact members *c* of up-direction switch 1A, conductors 55 and 56 and the resistor 57, to line conductor L2. Being now supplied with excitation proportional to the value of resistor 57, the generator GA supplies the elevator motor EMA with sufficient voltage to operate it at a slow speed, and the elevator car CA is, therefore, accelerated to such slow speed.

In closing, up-direction switch 1A also completes a self-holding circuit for its coil 58 by way of a circuit extending from line conductor L1, through conductor 59, contact members *a* of up-direction switch 1A, conductor 60, the coil 58 of up-direction switch 1A, and thence to line conductor L2, as previously traced.

To accelerate the car to intermediate speed, the operator may move the car switch CSA further in the counter-clockwise direction to complete a circuit for the intermediate-speed accelerating relay 3A, which circuit extends from line conductor L1, through conductor 40, contact members 41, 42 and 61, conductor 62, the coil 63 of accelerating relay 3A, conductor 64, contact members 65 of up-direction intermediate-speed inductor relay 1LUA, conductor 66, contact members 67 of down-direction intermediate-speed inductor relay 1LDA and conductors 68 and 49, to line conductor L2. Upon being actuated, intermediate-speed accelerating relay 3A closes its contact members *c* to shunt a portion of resistor 57 from the circuit of the separately excited generator field winding GFA, which circuit now extends, as previously traced, through conductor 55, thence through conductors 56 and 69, contact members *c* of relay 3A, conductor 70 and a portion of resistor 57, to line conductor L2. Relay 3A, in closing, also completes a self-holding circuit for its coil 63 which extends from line conductor L1, through conductor 71, contact members *a* of relay 3A, conductor 72, the coil 63 of relay 3A, and thence to line conductor L2, as previously traced.

Being now supplied with additional excitation, the generator GA supplies the motor EMA with a higher voltage, and the car CA is accelerated to its intermediate speed.

To accelerate the car to its highest speed, the operator may move the car switch CSA to its extreme position in the counter-clockwise direction, to thereby complete a circuit for the high-speed accelerating relay 4A, which circuit extends from line conductor L1, through conductor 40, contact members 41, 42 and 73, conductor 74, the coil 75 of high-speed accelerating relay 4A, conductor 76, contact members 77 of up-direction high-speed inductor relay 2LUA, conductor 78, the contact members 79 of down-direction high-

speed inductor relay 2LDA and conductors 80 and 49, to line conductor L2.

High-speed relay 4A, in closing, excludes the remainder of resistor 57 from the circuit of the separately excited generator field winding GFA, which circuit now extends, as previously traced, through conductor 55, thence, by way of conductors 56 and 81, contact members *c* of relay 4A and conductor 82, to line conductor L2. In closing, high-speed relay 4A also completes a self-holding circuit for its coil 75, which circuit extends from line conductor L1, through conductors 71 and 99, contact members *a* of relay 4A, conductor 83, the coil 75 of relay 4A and thence to line conductor L2, as previously traced.

Now, being supplied with maximum voltage by the generator GA, the elevator motor EMA accelerates to, and runs at, its highest speed.

If an intending passenger at the third floor desires to travel upwardly, he may operate the up-direction, floor button 3FU to thereby complete a circuit for the third floor up-direction actuating coil 3FRU by way of a circuit extending from line conductor L3 through conductor 84, the now closed floor button 3FU, conductor 85, the coil 3FRU and conductor 86, to line conductor L4. Now energized, coil 3FRU attracts its movable armature 87 to thereby release armature member 88. Upon being released, armature member 88 drops into the mercury pot 89 to thereby complete a call-registering circuit as far as segment 90 in line X of group 22 of the floor selector FSA, which circuit extends from line conductor L1, through armature member 88, the mercury pot 89, conductor 91, the resistor 3RU and conductor 92, to a junction point 93, whence one branch extends, by way of conductor 94, to the segment 90 of floor selector FSA, and a second branch continues, by way of conductor 95, to the corresponding segments of the floor selectors associated with all of the other cars in the bank.

When the elevator CA is still at a distance of almost two floors in advance of the third floor, the brush 22a on the movable arm MA of floor selector FSA connects the segments 90 and 96 of group 22 to thereby complete a circuit for the coil of blocking relay C2A, which circuit extends from line conductor L1, as previously traced, to segment 90, thence, through the movable brush 22a, the segment 96, conductor 97, the now closed contact members *c* of reversing relay 31, conductor 98, the coil 100 of blocking relay C2A and conductors 101 and 103 to the normally closed contact members of the bypass button BPA, thence, by way of conductor 104, to line conductor L2. In closing, blocking relay C2A places the resistor 102 in shunt relation to its coil 100, by way of the contact members *a* of blocking relay C2A, resistor 130

102, and conductor 103 to line conductor L2, as described.

Resistor 102 and coil 100, now being in parallel, the resistance of the call-registering circuit including the resistor 3RU is accordingly decreased, and, as a result, the current through, and the voltage drop across, the resistor 3RU are increased. If now, the second car CB should approach the third floor, and brush 22'a on movable arm MB of floor selector FSB should engage the segment 90', the voltage available to the blocking-relay C2B would be below the value necessary to actuate it, as previously described. Therefore, while the relay C2A or the similar relay C1A of car CA is energized, the corresponding relays of other cars in the bank are ineffective to complete the call-receiving circuits for those cars.

Upon closing, blocking relay C2A closes its contact member *b* to complete a call-receiving circuit for the operators signal lamp 2SLA, which circuit extends from line conductor L5, through conductors 121, 105 and 106, the signal lamp 2SLA, conductor 107, the contact members *b* of blocking relay C2A and conductor 108, to line conductor L6. The illumination of signal lamp 2SLA indicates to the operator that a stop is to be made at the third floor and that he should, therefore, center his car switch CSA to render the automatic stopping means effective. It will be understood, from the foregoing description of the starting and acceleration of the car, that the centering of the car switch does not immediately open the control circuits for the elevator motor.

When, in response to the visual signal, the operator centers his car switch CSA, a circuit is completed for energizing the coil of up-direction high-speed inductor relay 2LUA, which circuit extends from line conductor L1, through conductor 40, contact members 41, 42 and 109 of car switch CSA, conductors 110 and 111, contact members *d* of up-direction switch 1A, conductor 112, the coil of inductor relay 2LUA and conductors 113 and 49, to line conductor L2. As the car approaches the third floor, it passes the inductor plate associated with inductor relay 2LUA, causing this relay to open its contact members 77 to thereby interrupt the circuit for the coil 75 of high-speed accelerating relay 4A.

Relay 4A, therefore, opens its contact members *c* to reinsert a portion of resistor 57 in the circuit of the separately excited generator field winding GFA, thereby causing the elevator motor EMA to decelerate to its intermediate speed. Such deceleration will be initiated at a distance approximately one and one quarter floors in advance of the floor at which it is desired to stop.

Practically simultaneously with the de-energization of high-speed relay 4A, the

brush 22a leaves the segment 90 on the floor selector FSA, thereby interrupting the circuit to the coil of blocking relay C2A. However, prior to the time that brush 22a leaves segment 90, the brush 22b engages this segment and completes a circuit for the coil of blocking relay C1A. The actuation of relay C1A does not take place, however, until relay C2A is deenergized, since, until such time, the voltage available to its coil 114 is of a value below the actuating voltage of this coil. Upon being actuated, however, blocking relay C1A imposes the same blocking feature upon the call-receiving means of the other cars formerly imposed by blocking relay C2A.

The circuit for the coil 114 of blocking relay C1A now extends from line conductor L1, through the armature member 88, to segment 90, as previously described for relay C2A, thence, by way of brush 22b, of segment 116, conductor 117, contact members *b* of reversing switch 31, conductor 118, the coil 114 of blocking relay C1A, conductors 119 and 103 to the by-pass button BPA and conductor 104, to line conductor L2. Through its contact members *a*, blocking relay C1A places its associated resistor 115 in shunt relation to its coil, by way of conductor 120, contact members *a* of relay C1A, the resistor 115, and conductors 119 and 103, to line conductor L2, as previously traced. Therefore, as described for relay C2A, the voltage available to the blocking relays of all other cars in the bank is below the actuating value thereof.

Upon being actuated, blocking relay C1A closes its contact members *b* to complete a circuit for energizing the third floor up-direction hall lantern 3LUA, which circuit extends from line conductor L5, through conductor 121, the lamp 3LUA, conductor 123, segment 124, on the floor selector FSA, brush 21b on the movable arm MA, segment 125, conductor 126, contact members *a* of reversing switch 31, conductors 127 and 128, contact members *b* of blocking relay C1A, conductor 129, the now closed contact members *d* of high-speed relay 4A and conductor 130, to line conductor L6. It will be noted that the illumination of the hall lantern takes place when the elevator car is still at a distance of one and one quarter floors in advance of the floor at which the car is to stop, and that the intending passenger will, therefore, have sufficient time in which to position himself in front of the responding elevator.

It will also be noted that the illumination of the floor lantern does not take place unless deceleration has been initiated to stop the car at the floor in response to the call.

When the high-speed relay 4A is deenergized, a circuit is completed for the coil of up-direction intermediate-speed inductor relay 1LUA, which circuit extends from line conductor L1 through conductor 40, the con-

tact members 41, 42 and 109 of the car switch CSA, conductors 110 and 111, the contact members *d* of up-direction switch 1A, conductor 112, the coil of inductor relay 2LUA, conductor 133, the coil of inductor relay 1LUA, conductor 134, the normally closed contact members *b* of high-speed relay 4A and conductor 135, to line conductor L2. Accordingly, when inductor relay 1LUA passes its associated inductor plate mounted in the hatchway, its armature is actuated to open its contact members 65, thereby interrupting the circuit to the coil of intermediate-speed relay 3A.

Now deenergized, intermediate-speed relay 3A opens its contact members *c* to re-insert the remainder of resistor 57 into the circuit of the separately excited generator field winding GFA. As a consequence, the elevator motor is further decelerated to its low landing speed.

Immediately following the deenergization of relay 3A, which takes place at a point approximately mid-way between the second and third floors, the brush 22*b* leaves the segment 90 of the floor selector FSA, thereby interrupting the circuit to the coil of blocking relay C1A. At this time also, the brush 21*b* leaves the segment 124, but it will be noted that, at such time, the brush 21*c* is already in engagement with the segment 124.

After the deenergization of blocking relay C1A, the circuit for the hall lantern 3LUA is maintained through the normally closed contact members *d* of speed relay 3A by way of a circuit extending, as previously described, as far as conductor 127, thence, by way of conductor 136, the normally closed contact members *d* of relay 3A, conductor 137, the mechanical switch 138 and conductor 139, to line conductor LC.

Upon deenergization, intermediate-speed relay 3A also completes a circuit for the cancellation coil 3FCU associated with the third floor-hall button 3FU, which circuit extends from line conductor L3, through conductor 140, the coil 3FCU, conductor 141, conductor 142, the segment 143, the brush 24*c*, segment 144, conductor 145, contact members *d* of reversing switch 31, conductor 146, the normally closed contact members *e* of relay 3A, conductor 147, mechanical switch 148 and conductor 149, to line conductor L4.

Now being energized, the cancellation coil 3FCU attracts its armature member 88 to withdraw it from the mercury pot 89 and thereby cancel the registered call. It will be understood that the armature member 87 associated with coil 3FRU again engages the armature 88 when the latter is actuated by the energization of the coil 3FCU.

It will be noted that the blocking relay C1A is maintained effective until the cancellation of the registered call, and that such cancellation does not take place until the

car is within about six feet of the floor at which it was intended to stop. Further, the cancellation coil 3FCU is maintained in the energized position until the car again leaves the floor, since the segment on the floor selector FSA associated with this coil for the third floor extends slightly above the third-floor level on the floor selector FSA.

It has been observed that intending passengers, on approaching a bank of elevators, the floor lantern for one of which is illuminated, have a tendency to operate the call button in spite of the fact that such lantern indicates the approach of a car that is to stop. Even in such case, the call-registering circuit cannot be reestablished, since the cancellation coil 3FCU will prevent the armature 88 from dropping into the mercury pot 89.

To review briefly, then, according to my system, the first car to approach within a predetermined distance in advance of a floor for which a call exists is the only car the call-receiving means of which are effective to receive the registered call. Such blocking is effected, while the call is maintained in the registered condition, by the relays C2A and C1A, acting sequentially; and, after the call has been cancelled, the blocking feature is maintained by the cancellation means associated with the particular floor for that direction of travel.

When the intermediate-speed relay 3A is deenergized, it completes, through its contact members *b*, a circuit for the coil of stopping inductor relay SRA, which circuit extends from line conductor L1, through conductor 40 the contact members 41, 42 and 109 of the car switch CSA, conductors 110 and 111, the contact members *d* of up-direction switch 1A, conductor 112, the coil of inductor relay 2LUA, conductors 113 and 150, the coil of inductor relay SRA, conductor 151, normally closed contact members *b* of relay 3A and conductor 152, to line conductor L2. Accordingly, when relay SRA passes its associated inductor plate mounted in the shaft adjacent to the floor level, it actuates its armature to thereby open its contact members 47 and interrupt the circuit for the up-direction switch 1A. On being deenergized, up-direction switch 1A interrupts the circuit of the separately excited generator field winding GFA and sets the brake (not shown) to bring the car to a stop level with the floor.

In modern elevator installations employing speeds of six hundred feet or more per minute it is impossible to accelerate the elevator car from zero speed to high speed and then decelerate from high speed to zero speed again within the distance between two adjacent floor levels. It is necessary therefore, to provide more than one signal for the operator in order to indicate whether or not he

is to make a one floor run or a run of more than one floor, so that he may determine whether to operate at intermediate or at high speed. As described in the operation of the elevator leaving the first floor to make a stop at the third floor, when the car arrived within a predetermined distance in advance of the third floor, the lamp 2SLA was illuminated to notify the operator that he should center his car switch, such illumination taking place at a point far enough in advance of the signaled floor to permit deceleration from high speed.

As noted, I have provided a second operator's signal lamp 1SLA which will be illuminated while the car is standing at a floor when a call exists at the next adjacent floor, in which case, the operator must move his car switch only far enough to accelerate the car to intermediate speed.

If it be assumed that, while the car is standing at the third floor, an intending passenger at the fourth floor operates the hall push button 4FU, a circuit will be immediately completed for blocking relay C1A, which circuit extends from line conductor L1 through armature member 162, the mercury pot 163, resistor 4RU and conductor 165, to a junction point 166, whence one branch extends, by way of conductor 167, to segment 168 in group 22 of the floor selector FSA, and a second branch extends, by way of conductor 169, to the corresponding segments on the floor selectors of the other cars in the bank. Since the brush 22b is already in engagement with the fourth-floor segment 168, while the car is standing at the third floor, the circuit for the blocking relay C1A continues from segment 168, by way of the brush 22b, the segment 116 and conductor 117, to the blocking relay C1A, as previously described.

Since blocking relay C1A is energized, the hall lantern 4LUA will be immediately illuminated by way of a circuit extending from line conductor L5, through conductor 121, lantern 4LUA, conductor 170, segment 171 in group 21 of the floor selector FSA, and thence, through the brush 21b, as previously described, to line conductor L6.

Since the car is standing at the floor, another circuit is immediately completed for the one floor run signal lamp 1SLA, which circuit extends from line conductor L5, through conductors 121, and 105, the lamp 1SLA, conductor 172, the normally closed contact members e of direction switches 1A and 2A, in series relation, conductor 173, the contact members e of blocking relay C1A and conductor 174, to line conductor L6.

Having been signalled for a one-floor run, the operator will accelerate his car only to intermediate speed and will then center his car switch to render the automatic stopping means effective, in the manner previously described. It will be understood that the can-

cellation of the call will be identically as described for the original operation.

To proceed with the assumed operation, if it be assumed that the passenger who enters the car at the third floor wishes to leave the car at the fourth floor, he may operate the car button CA4 to thereby complete a circuit for the signal lamp 1SLA which circuit extends from line conductor L5, through conductors 121 and 105, the lamp 1SLA, conductor 172, contact members e of direction switches 1A and 2A, conductors 173 and 159, the segment 158 of group 23, the brush 23b, the segment 157, conductors 156 and 155, the now closed contact members of the car button CA4 and conductor 154 to line conductor L6. It will be noted that the car button CA4 will be maintained in its actuated condition by means of the latching member 161 until such time as the coil CCA of the re-setting device is energized.

Having received the one-floor-run signal, the operator will accelerate the car only to intermediate speed and center his car switch to set in motion the automatic stopping means, as described. In this case, since the blocking relay C1A was not energized, the floor lantern will not be immediately illuminated, but such illumination will take place immediately upon deenergization of the intermediate-speed relay 3A, as previously described. At this time also, the cancellation coil 4FCU will also be energized to provide the blocking feature already described for this coil.

If a passenger enters the car at the first floor and desires to leave it at the fourth floor, upon operating the car button C4A, a circuit is prepared for illuminating the two-floor-run signal lamp 2SLA, which circuit will be completed when the brush 23a engages the fourth-floor segment 157, which occurs when the car is at a distance of approximately one and three quarters floors in advance of the fourth floor. In this case, the operator accelerates his car to full speed and then centers his car switch to affect slow down and stop, as described. The illumination of the third-floor-hall lantern takes place in the manner described for the one-floor run in response to an inside call, as would the cancellation of the call and the blocking feature provided, in this case, by the third-floor cancellation coil.

From the foregoing description and an inspection of the floor selector FSA, it will be apparent that a car standing at any given floor blocks off the calls registered at the floor buttons for the next two floors in advance of the said floor, since the brush 22a is in engagement with the segment associated with the call-registering circuit for the second floor above, and the brush 22b is in engagement with the segment associated with the next adjacent floor.

It will be noted also, that the by-pass button is associated with the circuits for the blocking relays C1A and C2A, which are actuated in response to the operation of hall buttons by intending passengers, but that it is not associated with the circuit for the signal lamps. In other words, if, for any reason, the operator desires to by-pass a call registered by intending passengers, he 5 may do so and thereby render the blocking relays for his car ineffective to prevent the call-receiving means of the following car from receiving the registered call. He may not, however, cancel the calls registered by 10 passengers on the car who desire to leave the car at any floor. It will also be noted that, if an operator operates the by-pass button, he does not cancel the call register at the hall buttons, since the cancellation circuit 15 passes through normally-closed contact members of the intermediate-speed relay 3A.

It will be understood that, as the car approaches the terminal floor, the brush 25c engages a segment 175 in group 25 to thereby complete a circuit for the coil USA of the reversing switch 31 and the releasing coil CCA associated with the car buttons, which circuit extends from line conductor L3, through conductor 176, the coil CCA, conductor 30 25, the coil USA, conductor 178, segment 175, brush 25c, segment 179 and conductor 180 and 181, to line conductor L4.

Upon being energized, coil CCA actuates its armature member 182 to release the latching members associated with all of the car buttons. The coil USA, upon being energized, actuates the armature of reversing switch 31 to open the contact members *a*, *b*, *c*, and *d*, and to close the contact members 45 *a'*, *b'*, *c'*, and *d'*, thereby connecting the segments on the down, or right-hand, side of the floor selector FSA for energization through their respective circuits. It will be understood that the energization of coil USA 50 is only momentary, and that reversing switch 31 is maintained in the position established by the coils USA and DSA by means of the spring 32. It will also be understood that, as the car approaches the lower terminal, the coil DSA will be energized to condition the floor selector for travel in the up direction.

Since travel in the down direction is in all respects similar to travel in the up direction, with the exception that the up floor lanterns, the up floor buttons and the up direction switch are replaced by the corresponding down floor lanterns, down floor buttons and the down direction switch, it will 55 be unnecessary to describe such operation in detail.

The ease with which an existing system not embodying the blocking feature may be converted into a system of the type described 60 65 will be obvious from a consideration of the

call-receiving circuits usually associated with such existing systems.

Ordinarily, the call-receiving circuit comprises a hall button, some form of maintaining means therefor, some form of floor-selecting device and the call-receiving means. The cancellation means may or may not be effective at the time a car responds to the call. It will be obvious, however, that all cars that are within the predetermined distance of the floor at the time the call is registered or that approach within such predetermined distance before the call is cancelled are effective to receive such call. 75

It will be noted that, according to my system, the existing floor selector must be changed only to the extent of providing that the cancellation coil, when energized, shall be maintained so until the car leaves the next adjacent floor, and that I have changed the call-receiving circuit only to the extent of interposing the resistors 2RU, 2RD, etc., and the blocking relays C1A and C2A in the circuit of the hall buttons and the call-receiving means. In short, for a given installation, the only additional equipment required comprises two resistor members for each floor and two blocking relays for each of the cars. 80 85 90

It will be apparent, therefore, that I have provided a system wherein calls for service registered at any one floor for travel in a given direction may be transmitted to the call-receiving means of only the first car to approach within a predetermined distance of 95 said floor. I have further provided a system wherein a car standing at any one floor is the only car the call-receiving means of which are effective to receive calls for service at the next two floors in advance of the floor 100 at which the car is standing. I have provided also a system wherein, under certain conditions, the operator may by-pass registered calls but, in so doing, the call is maintained, and the call-receiving means of the 105 next of said cars are rendered effective to respond to the call. 110

In the foregoing specification, my system has been described as being applied to a manually controlled elevator but it will be apparent that my system is equally applicable to elevators employing any of the many well known forms of automatic control. Since, then, the described embodiment of my invention is merely illustrative, I do not desire to be limited to the details thereof except as defined in the appended claims. 115 120

I claim as my invention:

1. In a signaling system for a bank of elevator cars operable past a floor, passenger-operated call-registering means at said floor common to all of said cars for registering calls for service at said floor, call-receiving means individual to each of said cars for receiving said calls for service, electromagneti- 125 130

- cally operable means individual to each car and operable, upon application of voltage above a predetermined value, to complete a circuit to the call-receiving means for that car, a circuit for said floor having a portion common to all of said cars and including the call-registering means for that floor and having a plurality of branches, one for each of said cars, the branch circuit for each of said cars including the electromagnetically operable means for that car, means individual to each car and operable in correspondence with the position of said car with respect to said floor for completing the branch of said circuit including the electromagnetically operable means for that car when the said car approaches within a predetermined distance in advance of the said floor, and means also in the common portion of said circuit operable upon actuation of the said call-registering means, when one of said branch circuits is completed, to render the voltage available to the electromagnetically operable means for the others of said cars below the said predetermined value. 6 10 15 20 25
2. In a signaling system for a bank of elevator cars operable past a floor, passenger-operated call-registering means at the said floor common to all of said cars for registering calls for service at the said floor, call-receiving means individual to each car for receiving calls for service, electromagnetically operable means individual to each car and operable upon application of voltage above a predetermined value to complete a circuit to the call-receiving means for that car, a circuit for said floor having a portion common to all of said cars, said common portion including the call-registering means for that car and voltage-modifying means, and a plurality of branches, one for each of said cars, each branch including the electromagnetically operable means for that car, means individual to each car and operable correspondingly to the position of said car with respect to said floor for connecting the electromagnetically operable means for that car for actuation by said call-registering means when said car approaches within a predetermined distance in advance of said floor, and means responsive to the actuation of the electromagnetically operable means for any car for connecting additional voltage-modifying means in parallel relation to said actuated electromagnetically operable means to render the voltage available to the electromagnetically operable means for any others of the said cars below the said predetermined value. 30 35 40 45 50 55 60 65
3. In a signaling system for a bank of elevator cars operable past a floor, passenger-operated call-registering means at said floor common to all of said cars for registering calls for service at the said floor, call-receiving means individual to each car for receiving said calls for service, a call zone extending from within one predetermined distance in advance of the said floor to within a lesser predetermined distance in advance of the said floor within which the said call-receiving means are effective to receive said calls for service, electromagnetically operable means individual to each car and operable upon application of voltage above a predetermined value to complete a circuit for the call-receiving means for that car, a circuit for said floor having a portion common to all of said cars, said common portion including the call-registering means, and a plurality of branches, one for each of said cars, the branch for each car including the said electromagnetically operable means for that car, means individual to each car and operable correspondingly to the position of said car with respect to said floor for completing the branch of said circuit including the said electromagnetically operable means for that car while said car is within said call zone, and means also in the common portion of said circuit operable upon actuation of said call-registering means when any of said branch circuits is completed to render the voltage available to the electromagnetically operable means for the others of said cars below the said predetermined value. 70 75 80 85 90 95 100 105 110 115 120 125 130
4. In a signaling system for a bank of elevator cars operable past a floor, passenger-operated call-registering means at said floor common to all of said cars for registering calls for service at the said floor, means individual to each car for indicating that a call for service has been registered at said floor, electromagnetically operable means individual to each car and operable upon application of voltage above a predetermined value to complete a circuit for the indicating means for that car, a circuit for said floor having a portion common to all of said cars, said common portion including the call-registering means and having a plurality of branches, one for each of said cars, the branch for each car including the said electromagnetically operable means for that car, means individual to each car and operable correspondingly to the position of said car with respect to said floor for completing the branch of said circuit for said car when said car approaches within a predetermined distance in advance of the said floor, and means also in the common portion of said circuit and operable upon actuation of the said call-registering means when any of said branch circuits has been completed to render the voltage available to the electromagnetically operable means for any others of the said cars below the said predetermined value. 125
5. In a signaling system for a plurality of elevator cars operable past a floor, passenger-operated call-registering means at the said floor common to all of said cars for register- 130

- ing calls for service at the said floor, call-receiving means individual to each car for receiving the said calls for service, electromagnetically operable means individual to each 5 car and operable upon application of voltage above a predetermined value to complete a circuit for the call-receiving means for that car, a circuit for said floor having a portion common to all of said cars, and a plurality of 10 branches, one for each of said cars, the branch for each car including the electromagnetically operable means for that car, means individual to each car and operable correspondingly to the position of said car with respect to said 15 floor to complete the branch of said circuit including the electromagnetically operable means for that car when said car approaches within a predetermined distance in advance of the said floor, voltage-modifying means 20 also in said common portion of said circuit operable upon actuation of the said call-registering means, when one of said branch circuits is completed, to render the voltage available to the electromagnetically operable 25 means for any others of the said cars below the said predetermined value, and means in said completed branch circuit operable to render the voltage available to the electromagnetically operable means for the next of 30 said cars the branch circuit for which is completed above the predetermined value.
6. In a signaling system for a plurality of elevator cars operable past a floor, passenger-operated call-registering means at said floor 35 common to all of said cars for registering calls for service at the said floor, call-receiving means individual to each car for receiving the said calls for service, electromagnetically operable means individual to each car 40 and operable upon application of voltage above a predetermined value to complete a circuit for the call-receiving means for that car, a circuit for said floor having a portion common to all of said cars, said common portion 45 including the said call-registering means, and a plurality of branches, one for each of said cars, each branch circuit including the electromagnetically operable means for that car, means individual to each car and operable correspondingly to the position of said car with 50 respect to said floor for completing the branch of said circuit for that car while said car is within the first described zone, means in said common portion of said circuit and operable upon actuation of the said call-registering means when any branch circuit has been completed to render the voltage available to the electromagnetically operable 55 means for any others of the said cars below the said predetermined value, actuatable means for cancelling said calls for service, means for actuating said cancellation means and for rendering the said call-registering means ineffective to register calls for service, and means individual to each car and operable correspondingly to the position of said car 60 with respect to said floor for completing a circuit to the said actuating means while said car is within said second described zone and is operating at a slow speed.
7. In a signaling system for a plurality of elevator cars operable past a floor, passenger-operated call-registering means at said floor common to all of said cars for registering calls for service at the said floor, call-receiving means individual to each car for receiving calls for service at 70 said floor, the said call-receiving means being effective to receive calls for service within a zone extending from one predetermined distance in advance of the floor to a lesser predetermined distance in advance of the 75 floor to a lesser predetermined distance in advance of the floor and being ineffective to receive calls for service within a second zone extending from said lesser predetermined distance in advance of the floor to a second 80 lesser predetermined distance in advance of the floor, electromagnetically operable means individual to each car and operable upon application of voltage above a predetermined value to complete a circuit to the 85 call-receiving means for that car, a circuit for said floor, having a portion common to all of said cars, said common portion including the said call-registering means, and a plurality of branches, one for each of said 90 cars, each branch including the electromagnetically operable means for that car, means individual to each car and operable correspondingly to the position of said car with respect to said floor for completing the 95 branch of said circuit for that car while said car is within the first described zone, means in said common portion of said circuit and operable upon actuation of the said call-registering means when any branch circuit has been completed to render the voltage available to the electromagnetically operable 100 means for any others of the said cars below the said predetermined value, actuatable means for cancelling said calls for service, means for actuating said cancellation means and for rendering the said call-registering means ineffective to register calls for service, and means individual to each car and operable correspondingly to the position of said car 105 with respect to said floor for completing a circuit to the said actuating means while said car is within said second described zone and is operating at a slow speed.
8. In a signaling system for an elevator car operable past a floor, passenger-operated call-registering means at the floor for registering calls for service at said floor, and means operably responsive to the car answering a registered call for cancelling said registered call 110 and for rendering the call-registering means ineffective to register calls until completion of the answer to said registered call.
9. In a signaling system for an elevator car operable past a floor, passenger-operated call- 115

registering means at the floor for registering calls for service at the said floor, actuatable means for cancelling said calls for service, and means operably responsive to the elevator answering a registered call for actuating said cancellation means and maintaining it in its actuated condition for rendering the said call-registering means ineffective to register calls until completion of the answer to said registered call.

- 10 10. In a signaling system for an elevator car provided with means for decelerating to a stop at a floor, the combination with passenger-operated call-registering means at the floor for registering calls for service at said floor, of means operably responsive to the decelerating means for cancelling said registered calls when said car makes a stop at said floor, and means operably responsive to the position of said car while decelerating and stopping for maintaining said cancelling means in its operated condition to render said call-registering means ineffective to register calls until the completion of the stop.
- 15 15. In a signaling system for an elevator car provided with means for decelerating to a stop at a floor, the combination with passenger-operated call-registering means at the floor for registering calls for service at said floor, of means operably responsive to the decelerating means for cancelling said registered calls when said car makes a stop at said floor, and means operably responsive to the position of said car while decelerating and stopping for maintaining said cancelling means in its operated condition to render said call-registering means ineffective to register calls until the completion of the stop.
- 20 20. In a signaling system for an elevator car provided with means for decelerating to a stop at a floor, the combination with passenger-operated call-registering means at the floor for registering calls for service at said floor, of means operably responsive to the decelerating means for cancelling said registered calls when said car makes a stop at said floor, and means operably responsive to the position of said car while decelerating and stopping for maintaining said cancelling means in its operated condition to render said call-registering means ineffective to register calls until the completion of the stop.

25 25. In testimony whereof, I have hereunto subscribed my name this 5th day of October, 1929.

WILLIAM F. EAMES.

DISCLAIMER

1,822,085.—*William F. Eames*, Wilkinsburg, Pa. **SELECTIVE SIGNAL SYSTEM**. Patent dated September 8, 1931. Disclaimer filed February 3, 1934, by the assignee, *Westinghouse Electric & Manufacturing Company*.

Hereby enters this disclaimer to claims 8 and 9 which are in the following words, to wit:

“8. In a signaling system for an elevator car operable past a floor, passenger-operated call-registering means at the floor for registering calls for service at said floor, and means operably responsive to the car answering a registered call for cancelling said registered call and for rendering the call-registering means ineffective to register calls until completion of the answer to said registered call.

“9. In a signaling system for an elevator car operable past a floor, passenger-operated call-registering means at the floor for registering calls for service at the said floor, actuatable means for cancelling said calls for service, and means operably responsive to the elevator answering a registered call for actuating said cancellation means and maintaining it in its actuated condition for rendering the said call-registering means ineffective to register calls until completion of the answer to said registered call.”

[*Official Gazette February 20, 1934.*]
